UNITED STATES PATENT OFFICE.

JOHN H. BENNETT, OF WORCESTER, MASSACHUSETTS.

SPINNING-RING HOLDER.

SPECIFICATION forming part of Letters Patent No. 678,980, dated July 23, 1901.

Application filed April 23, 1900. Serial No. 13,839. (No model.)

To all whom it may concern:

Be it known that I, JOHN H. BENNETT, a citizen of the United States, and a resident of Worcester, in the county of Worcester and 5 Commonwealth of Massachusetts, have invented certain new and useful Improvements in Spinning-Ring Holders, of which the following is a specification, reference being had to the accompanying drawings, forming a part 10 of the same, in which—

Figure 1 represents a top view of my improved spinning-ring holder with a double-flanged spinning-ring placed in position thereon. Fig. 2 is a side elevation of the same. 15 Fig. 3 is a sectional view on line 3 3, Fig. 1. Fig. 4 is a sectional view on line 4 4, Fig. 1; and Fig. 5 represents a top view of a portion 20 of the ring-holder with the spinning-ring removed and with the location of the outer edge of the spinning-ring flange indicated by a broken line concentric with the ring-holder.

Similar reference-letters refer to similar parts in the different views.

The spinning-ring holder forming the subject of my present invention is designed to be attached to a rail of a spinning-frame and to hold thereon a duplex spinning-ring or one provided with two circular races united by a tubular neck.

The object of my invention is to provide a holder for spinning-rings having means integral with the holder for maintaining the ring in proper position and holding it against lateral movement and retain it in close contact 35 with the holder and concentric therewith; and it consists in the novel features of construction, as hereinafter described, and pointed out in the annexed claims.

Referring to the drawings, A denotes one 40 of my improved spinning-ring holders, consisting of a flat annulus preferably provided with notches or slots A' to receive attaching-screws by which it may be secured to the supporting-rail of the spinning-frame. In a circle concentric with the ring-holder I stamp, 45 by means of suitable dies, three projecting lips B, which are raised above the upper surface of the holder, with their free edges B' adapted to slightly overlap the outer edge of 50 the flange C of a spinning-ring C'.

The lip B, when struck up from the sheet metal forming the ring-holder, is pressed by

suitable dies into a slightly-curved shape, so its overlapping edge will exert a downward pressure upon the edge of the flange C and 55 retain it by the elasticity of the lip in close contact with the upper surface of the ring-holder. The lips B are preferably of equal length and have equal spaces between them, so as to bear at three equidistant points upon 60 the flange of the spinning-ring. When the flange of the spinning-ring is to be inserted beneath the free edges B' of the lips B, pressure is applied to the ring to crowd the edges of the lips B apart and allow the ring to be 65 sprung into position. In order to allow the ring to be readily sprung into position, the free edges B' of the lips B but slightly overlap the flange C, and as the lips B are curved, so as to cause the pressure of their free edges to be 70 exerted downwardly upon the edge of the flange, the spinning-ring would be capable of a slight movement beneath the edges of the lips B, and in order to prevent this movement and to cause the ring to be held absolutely concentric with its holder I stamp a pair of short 75 lips D upon each side of the retaining-lips B by raising a portion of the sheet metal above its surface, as in the case of the lips B; but instead of making the edges of the short lips 80 D to overlap the flange C of the spinning-ring I raise the lips D just far enough to bring their edges D' into the plane of the flange C, and I make the edge D' of the lips D to coincide with a circle E, Fig. 5, concentric with 85 the ring-holder and of the same diameter, so that when the spinning-ring is placed in position the edge of the flange C will abut against the free edges D' of the short lips D and hold the ring from lateral movement. By providing 90 the short lips D with their free edges abutting against the edge of the flange of the spinning-ring I am able to make the lips B longer and more elastic, with their pressure exerted wholly in a downward direction, thereby holding 95 the spinning-ring more closely in contact with the holder and facilitating the introduction of the flange C beneath the lips.

What I claim as my invention, and desire to secure by Letters Patent, is—

1. As an article of manufacture, the within-described spinning-ring holder consisting of an annular plate adapted to extend beneath and support the spinning-ring, and having

- means for attachment to the rail of a spinning-frame, of a series of elastic yielding lugs integral and concentric with said plate, with their free edges adapted to overlap the flanged 5 base of the spinning-ring, and a series of short unyielding lugs between said yielding lugs adapted to bear against the outer edge of the spinning-ring flange and hold it from lateral movement, substantially as described.
- 10 2. A spinning-ring holder consisting of an annular plate A with its inner edge extending beneath the flanged base of a spinning-ring, a series of short lugs B overlapping the outer edge of the flanged base of the ring and 15 capable of yielding outwardly to allow the ring to enter between them, and a pair of lugs D arranged at the ends of said yielding lugs, and bearing against the outer edges of

the flanged base of the ring to hold it from lateral movement, substantially as described. 20

3. In a spinning-ring holder, the combination with a plate forming a support for the ring, of a series of lips arranged to overlap the flange of the ring and a series of lips bearing against the edge of the flange of the 25 ring and hold it from lateral movement, substantially as described.

In testimony whereof I have signed my name to this specification, in presence of two subscribing witnesses, this the 16th day of 30 April, 1900.

JOHN H. BENNETT.
